UNITED STATES PATENT OFFICE.

CHARLES S. FRANKLIN, OF BUCKHURST HILL, AND WILLIAM J. PICKEN, OF SOUTH-END-ON-SEA, AND JOHN GLOVER ROBB, OF READING, ENGLAND, ASSIGNEES TO RADIO CORPORATION OF AMERICA, A CORPORATION OF DELAWARE.

AERIAL SYSTEM FOR WIRELESS SIGNALING.

Application filed November 16, 1920, Serial No. 424,351, and in Great Britain November 17, 1919.

The object of this invention is to provide an improved wireless aerial system which shall have special directive properties and shall be particularly suited for duplex working and for preventing interference from other wireless stations or from atmospherics.

It is known that if two frame-aerials or two aerial systems, each consisting of two frames at right angles and combined in a radiogoniometer, be separated by a distance comparable to the wave length of the signals to be received and be arranged to affect a common receiver in a suitable manner, then that receiver will not be affected by signals from certain directions. Such aerial systems are described, for instance, in British specifications Nos. 24,098 of 1914 and 5,783 of 1915.

According to this invention we combine with each of such frames or with each of such systems of two frames at right angles, a plain non-directive aerial in a manner that has before been proposed for combining a plain aerial with a single frame aerial so that each of the systems has a polar reception diagram approximating to a cardioid. Or we connect the midpoint of the radiogoniometer coils to earth, thereby giving the same effect.

Signals received in the two systems are then caused to act simultaneously on a common receiver situated at some point preferably midway between the systems, arrangements being made to mis-phase the signals from the two systems relatively to each other.

We have found that the whole combination so constituted has very pronounced and advantageous directive properties.

Thus, for example, it is possible to obtain at the same time zero for signals from one direction, maximum for signals from the opposite direction and zero for signals from two other directions which can be varied by the amount of mis-phasing. Or, alternatively, we can obtain greatly increased sensitivity for signals from one direction combined with extreme insensitivity for signals of the same wave length coming from any direction within an arc extending about 65° on either side of the direction opposed to that of great sensitivity.

The invention is illustrated in the accom-

panying drawing, in which, Fig. 1 shows diagrammatically a circuit arrangement embodying our invention, and Figs. 2 to 5 show various reception diagrams obtainable by the use of the invention.

A and B are two aerial systems separated by a distance comparable to the wave length, C being apparatus situated approximately midway between them where signals received by the separated systems are suitably combined and rectified so as to be audible in the telephones.

The apparatus at A is a replica of that at B.

Two frames at right angles are tuned to incoming waves by means of variable condensers E and connected to the coils of the radiogoniometer D¹, D², D³, D⁴. A search coil F is coupled to these radiogoniometer coils and also to a circuit G connecting to the midway station.

Two condensers H of equal value are connected together in series and arranged in parallel with the variable condensers E, and the midpoint of these condensers is then the middle of the frames in a symmetrical system. These midpoints are connected together and through a coupling coil I and tuning condenser J to earth.

By suitable tuning and coupling of the search coil circuit and the plain aerial circuit a cardioid diagram of reception is obtained.

When two systems are arranged as described with cardioid polar diagrams and the currents received from them are combined in the midway station a variety of polar diagrams of reception are obtainable.

If two such systems, separated by one quarter of the wave length and disposed along the line of reception of the signals which are to be received, are combined with no misphasing, a polar diagram of reception as shown in Figure 2 is obtained.

Figure 3 shows a polar diagram of reception when the circuit X forming the connection to the midway station for the front system B is slightly mistuned so that the inductance effect predominates to produce a lag of current of 22.5° relative to the applied electromotive force produced by the incoming signals which gives rise to that current. Similarly in the system A the capacity effect

is made to predominate and thereby produce a lead of current of 22.5° relative to the applied electromotive force.

Figure 4 shows a polar diagram of reception when the system B is misphased to produce a lead of current of 22.5° and the system A misphased to produce a lag of 22.5° .

By different degrees of misphasing a variety of polar diagrams of reception are obtained in which one zero of reception is fixed and two zeros of reception are capable of being altered at will.

If the systems are arranged so that the line joining them is truly in the direction of the distant station from which it is desired to receive signals, then all the polar diagrams of reception will be symmetrical.

If, however, the line joining the two systems is not truly in the direction of the station from which it is desired to receive signals, then the polar diagrams of reception are asymmetrical as shown in Figure 5.

Therefore, by suitable arrangement of the two systems relative to the direction of the station from which signals are to be received, and by suitable misphasing of the two systems when combining, great control can be obtained over the polar diagram of reception, thereby permitting the elimination of undesirable signals and atmospherics.

What we claim is:

1. In radio signaling apparatus the combination of a plurality of directional aerials each aerial being constructed to have also a non-directional characteristic, means for indicating oscillations, means for transferring to said indicating means a portion of the energy received by each antenna by virtue of its directional characteristic, means for transferring to said indicating means a portion of the energy received by each antenna by virtue of its non-directional characteristic.

2. In radio signaling apparatus the combination of a plurality of direction finding aerials, each direction finding aerial being grounded at a substantially neutral point

whereby it has also a non-directional characteristic, indicating apparatus, means for impressing upon said indicating apparatus a portion of the energy received by said direction finding aerial in accordance with its direction finding characteristic, means for impressing upon said indicating apparatus a portion of the energy present in said ground connection and means for adjusting the phase of the several currents with respect to each other.

3. In a wireless receiving station, the combination of two aerial systems spaced apart and in the general line of desired reception, and each comprising a directional portion and a non-directional portion and a common means for indicating the resultant and the energy received upon each aerial system.

4. In a wireless receiving station, the combination of a plurality of aerial systems spaced apart and in the general line of desired reception and each comprising a plurality of aerial sections, one of said aerial sections being directive and another non-directive, and a common means for indicating the resultant of the energy received upon each aerial system.

5. In a wireless receiving station, the combination of a plurality of aerial systems spaced apart an appreciable fraction of the wave length of the signals to be received and in the general direction of desired reception, and each comprising a directional portion and a non-directional portion, a common means for indicating the resultant of the energy received upon each aerial system and means for regulating the phase of each current component of the energy absorbed by each aerial system to vary the directional characteristic of said station.

In testimony that we claim the foregoing as our invention we have signed our names this twenty-eighth day of October, 1920.

JOHN GLOVER ROBB.

CERTIFICATE OF CORRECTION.

Patent No. 1,717,674.

Granted June 18, 1929, to

CHARLES S. FRANKLIN ET AL.

It is hereby certified that error appears in the printed specification of the above numbered patent requiring correction as follows: Page 2, line 64, claim 3, for the word "and" read "of"; and that the said Letters Patent should be read with this correction therein that the same may conform to the record of the case in the Patent Office.

Signed and sealed this 10th day of September, A. D. 1929.

**M. J. Moore,
Acting Commissioner of Patents.**
